FRED S. EDINGER, OF BERKELEY, CALIFORNIA, ASSIGNOR OF ONE-HALF TO ARCHIBALD BORLAND, OF OAKLAND, CALIFORNIA.

FLEXIBLE-CONCRETE-SLAB-REVESTMENT CONSTRUCTION FOR EMBANKMENTS.

1,164,707.

Specification of Letters Patent. Patented Dec. 21, 1915.

Application filed February 16, 1915. Serial No. 8,461.

To all whom it may concern:

Be it known that I, FRED S. EDINGER, a citizen of the United States, residing at Berkeley, in the county of Alameda and State of California, have invented certain new and useful Improvements in Flexible-Concrete-Slab-Revetment Construction for Embankments, of which the following is a specification.

10 My invention relates, in general, to revetments for the protection of embankments, and, particularly to that type of revetment-facings which are composed of concrete-slabs, flexibly united to enable the facing to 15 conform itself to the inequalities of the surface and to maintain itself in close relation thereto. Quite commonly it is the practice to unite the slabs by wires. These wires being exposed, soon corrode and leave the facing 20 subject to dismemberment.

It is the object of my invention to provide a concrete-slab revetment-facing which shall be flexible and yet be fully protected in its articulations or interlocking joints, the slab-units being simple in construction and adapted to be readily laid together.

To this end my invention consists in the novel flexible concrete slab-revetment construction which I shall hereinafter fully describe, by reference to the accompanying drawings, in which—

Figure 1 is a plan of my construction showing the slab-units in their best shape. Fig. 2 is a section on the line $x-x$ of Fig. 1. Fig. 3 is a fragmentary plan view showing a modification in the shape of the slab-units. Fig. 4 is an elevation, enlarged, of the point-fastening button in its best form, the view being on the line $y-y$ of Fig. 5. Fig. 5 is 40 a plan view of the point portions of a group of slab-units, the top of the button being broken. Fig. 6 is an elevation of the point-fastening button for use along the lower edge of the construction, said view being on the line $z-z$ of Fig. 7. Fig. 7 is a plan view 45 of the point portions of a group of slab-units of the lowermost row, the point fastening button being broken on top. Fig. 8 is a sectional view showing a modification of 50 the point fastening button, on the line $w-w$ of Fig. 9. Fig. 9 is a broken plan view of the modification of Fig. 8. Fig. 10 is a sectional view showing still another modification of the point fastening button on the line $v-v$ of Fig. 11. Fig. 11 is a broken 55 plan view of the modification of Fig. 10.

In Fig. 2—1 is an embankment, which in this case, for the sake of illustration, is shown as a levee, the face of which is to be protected from the wave wash of a body of 60 water 2, or from the ravages of insects or crustaceans, such for example as crayfish. The facing is composed of concrete-slab units 3. These may be reinforced or not as may be desired. Their best form or shape, 65 for the purpose of universal flexibility, is triangular, as shown in Fig. 1. Their meeting edges are provided or formed with articulating instrumentalities which are integral with the body of the slab and of a 70 nature which, while yielding flexibility on every side, will interlock them from relative sliding movement, that is, movement in a direction parallel or substantially parallel with the face of the embankment. The best 75 form of these articulations I consider those here shown, namely, the complementary interfitting integral concrete tongues 4, on each side of each slab. The meeting points of these slab-units must be assembled in a 80 lock which will permit flexibility, and still will prevent them from drawing apart in a direction away from or perpendicular to the face of the embankment. This lock, in its best form, is a concrete-button and the best 85 and simplest shape of the button is that shown in Figs. 1 to 5, and indicated by 5, which form comprises two flanges and a shank. The points of the slabs 3 are merely 90 slipped freely between the button flanges and have sufficient play therein in a direction to and from the face of the embankment to not interfere with the general flexibility of the articulated revetment and yet 95 not enough movement to allow the units to separate. The button 5 has its shank of circular or other suitable section to receive the meeting points of the six slab-units which constitute a group of the hexagonal 100 pattern formed by the triangular slabs, but at the lower edge of the revetment construction, where only three slab-units unite in a point, the fastening at this edge is a button 6, the shank of which is triangular in section, and the point of the middle slab of 105 each group of three is cut off at 7 to lie against one of the flat sides of the shank of the button, this cut off being far enough

back, as is best shown in Fig. 7, to permit the sides of the other two slabs, the points of which are not cut off, to lie against the other two sides of said shank. Thus the construction along its lower edge is locked together. It is best at the top edge of the construction to form the slabs with a hook 8 adapted to engage the hook 9 of a concrete anchor 10 on top of the embankment, as seen in Fig. 2.

10 The revetment construction as thus described is capable of modifications in several particulars without departing from my invention. Some of these I will now point out.

15 Though the best form of the slab unit, as I have already stated, is triangular, because it yields universal flexibility, other shapes may be employed. Thus in Fig. 3 I show 20 the slab-units 3 as square, and in this case the articulations on each side will be double ones, as shown at 11, to keep the units from slipping in either direction.

25 The point fastening button may also be modified. Thus in Figs. 8 and 9 I show a button 12 composed of initially separable sections—lower and upper. Between the two sections, half in each, is formed a groove 13, in which the enlarged or knobbed points 30 14 of the slab-units 3 are articulated. A bolt 15 embedded in the lower section passes into a socket 16 in the other section and there receives a nut 17. A filling 18 of concrete then seals up the socket, so that the 35 bolt is not exposed. This button 12 serves as a more complete lock than the simple button 5 heretofore described.

40 Another modification of the button is shown in Figs. 10 and 11. In this form the button 19 is formed with a peripheral hook 20, and the ends of the slab-units 3 are formed with a hook 21. These hooks articulate and are locked in place by a concrete 45 plug 22, which is itself fastened by a bolt 23, the head of which is covered by a filling 50 of concrete 24. This form of fastening is also a complete lock for the meeting points of the slab-units. The simplest form, however, and that which I deem sufficient for all 55 practical purposes is the button 5. It may be pointed out, however, that with the form of point-fastening-buttons shown in Figs. 8 and 9 and in Figs. 10 and 11, the slab-units will be both articulated and locked even if 60 the lock articulations on the meeting edges of the units be omitted and said edges be plain and simply laid up to meet and flex against each other.

I claim:—

60 1. A flexible concrete-slab-revetment construction for embankments, composed of concrete slab units, each unit being formed, on each of its edges, with an integral concrete complementary joint member of a flexible articulation, adapted to lock the units against 65 relative movement in a direction perpendicular to the face of the embankment.

units against relative movement in a direction parallel with the face of the embankment; and independent concrete fastening-members adapted to freely receive the meeting points of the slab-units and lock them against separation in a direction perpendicular to the face of the embankment.

2. A flexible concrete-slab-revetment construction for embankments, composed of concrete slab units, each unit being formed, 75 on each of its edges, with an integral concrete complementary joint member of a flexible articulation, adapted to lock the units against relative movement in a direction parallel with the face of the embankment; and fastening instrumentalities for the meeting points of the slab-units consisting of independent concrete buttons adapted to receive and flexibly articulate said points and lock them against separation in a direction perpendicular to the face of the embankment.

80 3. A flexible concrete-slab-revetment construction for embankments, composed of concrete-slab units, each unit being of triangular contour and formed on each of its edges with an integral concrete complementary joint member of a flexible articulation, adapted to lock the units against relative movement in a direction parallel with the face of the embankment; and independent 90 concrete fastening-members adapted to freely receive the meeting points of the slab-units and lock them against separation in a direction perpendicular to the face of the embankment.

85 4. A flexible concrete-slab-revetment construction for embankments, composed of concrete-slab units, each unit being of triangular contour and formed on each of its edges with an integral concrete complementary joint member of a flexible articulation, adapted to lock the units against relative movement in a direction parallel with the face of the embankment; and fastening 95 instrumentalities for the meeting points of the slab-units consisting of independent concrete buttons adapted to receive and flexibly articulate said points and lock them against separation in a direction perpendicular to the face of the embankment.

100 5. A flexible concrete-slab-revetment construction for embankments, composed of concrete-slab-units, each unit being of triangular contour and formed on each of its edges with complementary hooks flexibly articulating said units while locking them against relative movement parallel with the face of the embankment; fastening instrumentalities for the meeting points of the slab-units, consisting of independent concrete buttons composed of lower and upper flanges with a connecting shank, said buttons freely receiving the points of the slab-units and locking them against separation in a direction perpendicular to the face of the embankment.

the embankment; and fastening instrumentalities for the meeting lower points of the lowermost row of slab-units consisting of flanged concrete buttons with a shank of triangular section, the slabs of said lowermost row having the middle unit cut back at its point to rest against one of the faces of the button shank, and the points of the adjacent units being uncut and lying against the other faces of said shank.

6. A flexible concrete-slab-revetment construction for embankments, composed of concrete-slab units, and fastening instru-

mentalities for the meeting points of the slab-units consisting of independent concrete buttons adapted to flexibly articulate said points and to lock the units against separation.

In testimony whereof I have signed my name to this specification in the presence of 20 two subscribing witnesses.

FRED S. EDINGER.
